(57) **CLAIM**

The ornamental design for an overhang portion of a paper feed machine, as shown and described.

DESCRIPTION

FIG. 1 is a perspective view of an overhang portion of a paper feed machine showing our new design;

FIG. 2 is a front elevational view thereof;

FIG. 3 is a top plan view thereof;

FIG. 4 is a bottom plan view thereof; and,

FIG. 5 is a right side elevational view thereof, the left side elevational view being a mirror image thereof.

The broken line showing of portions of the paper feed cassette tray and the copy machine is for illustrative purposes only and forms no part of the claimed design.
